DESIGN.

No. 29,526.

Patented Oct. 18, 1898.

C. F. CLOTHIER, JR. & T. A. BURROWS.

REAR STAY FOR BICYCLES.

(Application filed July 22, 1898.)

UNITED STATES PATENT OFFICE.

CONRAD F. CLOTHIER, JR., AND THOMAS A. BURROWS, OF PHILADELPHIA,
PENNSYLVANIA.

DESIGN FOR A REAR STAY FOR BICYCLES.

SPECIFICATION forming part of Design No. 29,526, dated October 18, 1898.

Application filed July 22, 1898. Serial No. 686,623. Term of patent 3½ years.

To all whom it may concern:

Be it known that we, CONRAD F. CLOTHIER, Jr., and THOMAS A. BURROWS, citizens of the United States, residing at Philadelphia, in the county of Philadelphia and State of Pennsylvania, have invented and produced a certain new and original Design for the Rear Forks or Stays of Bicycles, of which the following is a specification, reference being had therein to the accompanying drawings, forming part thereof.

Figure 1 of the drawings is a side view of the rear stays of a bicycle of our design, showing one of each of the upper and lower stays. Fig. 2 is an end view of the same, showing the stays on both sides. Figs. 3 and 4 are sections of the stays at the two ends.

A is the seat-post cluster.

B is the hanger-shell.

20 C is the rear-fork end.

D is the upper fork.

E is the lower fork.

F is the center-post or mast.

As shown in the drawings, the leading or material features of our design consist in that 25 the tubes or hollow rods forming the rear stays are in straight lines from the connection with the rear-fork end to the seat-post cluster and to the hanger-shell, respectively, and in that these hollow rods or tubes are 30 tapered from the seat-post cluster and the hanger-shell, respectively, to the rear-fork end, and also in that the stays are elliptical in form.

Having described our invention, what we 35 claim as new, and desire to secure by Letters Patent, is—

The design for the rear stay of a bicycle, as herein shown and described.

CONRAD F. CLOTHIER, JR.
THOS. A. BURROWS.
